MEAT CUTTING BAND SAW

William Lasar, Los Angeles, Calif.

Application September 30, 1947, Serial No. 141,661

Term of patent 14 years

(Cl. D55—1)

To all whom it may concern:

Be it known that I, William Lasar, a citizen of the United States, residing at Los Angeles, in the county of Los Angeles and State of California, have invented a new, original, and ornamental Design for a Meat Cutting Band Saw, of which the following is a specification, reference being had to the accompanying drawing, forming a part thereof.

Fig. 1 is a perspective view of a meat cutting band saw, embodying the new design;

Fig. 2 is a rear perspective view of the same; and

Fig. 3 is a vertical sectional view of the same taken along the plane III—III of Fig. 2.

The side portions, not shown, are substantially plain.

The dominant features of my design reside in the portions shown in full lines.

I claim:

The ornamental design for a meat cutting band saw, as shown and described.

WILLIAM LASAR.
